UNITED STATES PATENT OFFICE.

HARRISON HEBBARD, OF EAST ORANGE, NEW JERSEY, ASSIGNOR TO DOMINICK & HAFF, OF NEW YORK, N. Y.

DESIGN FOR A POT OR SIMILAR ARTICLE.

45,935.

Specification for Design.

Patented June 16, 1914.

Application filed February 12, 1914. Serial No. 818,418. Term of patent 7 years.

To all whom it may concern:

Be it known that I, HARRISON HEBBARD, a citizen of the United States, and a resident of East Orange, in the county of Essex and State of New Jersey, have invented a new, original, and ornamental Design for a Pot or Similar Article, of which the following is a specification, reference being had to the accompanying drawing, forming a part hereof.

2 is a horizontal section substantially on the line 2, 2 of Fig. 1 omitting the sprout, a portion of the handle and the interior configuration of the pot.

I claim:

The ornamental design for a pot or similar article.

HARRISON HEBBARD.
